UNITED STATES PATENT OFFICE

JOHN BONNER, OF TIBURON, ASSIGNOR OF ONE-HALF TO CHARLES W. MOTT, OF SAN FRANCISCO, CALIFORNIA.

STEERING APPARATUS.

SPECIFICATION forming part of Letters Patent No. 548,289, dated October 22, 1895.

Application filed November 5, 1894. Serial No. 527,957. (No model.)

To all whom it may concern:

Be it known that I, JOHN BONNER, a citizen of the United States, residing at Tiburon, in the county of Marin and State of California, 5 have invented certain new and useful Improvements in Steering Apparatus; and I do declare the following to be a full, clear, and exact description of the invention, such as will enable others skilled in the art to which 10 it appertains to make and use the same.

My invention relates to improvements in vessel-steering apparatus, and more especially to that class of steering apparatus in which fluid-pressure-actuated mechanism is employed in conjunction with a hand-wheel; and 15 its novelty will be fully understood from the following description and claim when taken in conjunction with the annexed drawings, in which—

20 Figure 1 is a diagrammatical view, illustrating my improved apparatus, with some of the parts in section, some in perspective, and others in elevation. Fig. 2 is an elevation of the hand-wheel. Fig. 3 is an enlarged sectional view of the piston cylinder and valve, and Fig. 4 is a transverse section taken in the plane indicated by the line $x-x$ of Fig. 3.

25 In the said drawings similar letters designate corresponding parts in all of the several 30 views, referring to which—

A indicates a rudder, which may be of the usual construction, having a post or stock a and a tiller b .

B indicates a piston-cylinder.

35 C indicates a piston which is arranged in the cylinder and has its rod D extended through the heads at opposite ends of the same, and E indicates the casing of my improved valve. This casing E has a head d at one end provided with a fluid-induction port e , and at its opposite end it has a head f , provided with a stuffing-box and with a passage g for the valve-stem h . Said casing E is furthermore provided in its inner side at 40 its middle with an annular groove i , which communicates with the exhaust j , and on opposite sides of said groove i it is provided with the annular grooves k l , which communicate with the ports m n , which in turn communicate with the pipes p q , leading to opposite ends of the piston-cylinder. The annular grooves i k l in the casing E are covered 45

55 by the bushing F, which has the circular series of ports r s communicating with the grooves k l , respectively, and the port t communicating with the groove i , and is designed to receive the slide-valve G. (Better illustrated in Fig. 3.)

The valve G is hollow with an apertured head u at one end for connection to the stem h , and it is provided at opposite ends with the enlargements v w , having suitable packing-rings, and between said enlargements has the reduced portion x , forming a space adapted to effect communication between the bushing- 65 ports r and t and between the ports s and t , according to the position of the valve.

60 One end of the piston-rod D is connected with the rudder A by a cable or chain y , and the opposite end is connected with the rudder 70 by a cable or chain z , which takes around a drum H, arranged between the piston-rod and the rudder, and consequently it will be seen that when the piston is moved in the direction indicated by arrow (see Fig. 1) the rudder will 75 be swung to starboard, and when the piston is moved in a direction opposite to that indicated by arrow the rudder will be caused to swing toward the port or larboard side of the vessel. 80

75 The movements of the piston are controlled by the valve G, and when said valve is in the position shown in Fig. 3 the fluid will pass from the induction-port e , through the ports s , in the bushing F, and through the pipe q to 85 the piston-cylinder on the left-hand side of the piston and move the said piston in the direction indicated by arrow, while the fluid in the cylinder on the right-hand side of the piston will pass through the pipe p , the casing-port m , the bushing-ports r , the space formed by the reduced portion x of the valve, the bushing-port t , and the exhaust-port j to the open air. When the piston is moved the full extent toward the left, the fluid will pass from 90 the cylinder on the left-hand side of the piston through the pipe q , the casing-port n , the bushing-ports s , the space formed by the reduced portion x of the valve and the bushing-port t , and exhaust-port j to the open air, and 95 simultaneously with the exit of fluid from the piston-cylinder on one side of the piston fluid will pass from the induction-port e , through the valve, the bushing-ports r , the casing-port 100

m, and the pipe *p* to the piston-cylinder on the right-hand side of the piston, and move the piston in a direction opposite to that indicated by arrow.

5 It will be readily noticed that when the valve *G* is moved in either direction to reverse the direction of movement of the piston *C* the ports *r* and *s* will be simultaneously uncovered, and consequently no fluid can escape 10 from the cylinder on one side of the piston until fluid is admitted on the opposite side of the piston, whereby it will be seen that at the end of every stroke of the piston there will be a cushion of fluid which, in the event of the 15 rudder-cable breaking, will prevent the piston from knocking out the head of the cylinder.

When the valve is moved to the position shown in Fig. 1, both sets of ports *r* *s* will be 20 covered and fluid and air will be locked in the piston-cylinder on opposite sides of the piston, and consequently the piston and the rudder connected therewith will be held in the position they occupy when the valve is 25 moved against movement in either direction.

The drum *H*, which is journaled in suitable bearings and has hand-wheels *I* at its ends, is gradually increased in diameter from its middle to its opposite ends, and is grooved, as 30 shown, to seat the coils of the cable, which is preferably connected to the drum at the middle thereof, as illustrated. The coils of cable are wound upon the drum from the middle toward opposite ends thereof, and consequently 35 when the drum is rotated the length of cable paid out at each rotation will be gradually diminished, while the length of cable taken up at each rotation will be gradually increased, which will result in the cable being kept perfectly taut at all times, which is an important 40 desideratum in this class of apparatus, as is obvious. My improved drum is furthermore advantageous, for the reason that there is no liability of the cable slipping off the ends of 45 the drum.

The drum *H* and the hand-wheels *I* at opposite ends of the same may be and preferably are placed in the pilot-house of the vessel, as is also the lever *J* for manipulating the 50 valve *G*. This lever *J* is of bell-crank form and is connected by a link *K* with another bell-crank lever *L*, which in turn is connected to the valve-stem *h*, whereby it will be seen that when the lever *J* is moved motion will 55 be transmitted to the valve. A lever, such as *J*, is preferable for moving the valve, but, as is obvious, any suitable device connected in any suitable manner with the valve may be employed.

60 When it is desirable for any reason to move the rudder by hand, independent of the fluid-

pressure mechanism, it is simply necessary to move the valve to the position shown in Fig. 3 and shut off the supply of fluid, when the vessel may be steered in the ordinary manner through the medium of the hand-wheels *I* and drum *H*.

Steam, compressed air, water, or other fluid under pressure may be employed in my improved apparatus to move the piston *C*, but I 70 generally prefer to employ steam for obvious reasons.

I have in some respects specifically described the construction and relative arrangement of the parts of my improved apparatus 75 in order to impart a full, clear, and exact understanding of the same; but I do not desire to be understood as confining myself to such construction and arrangement, as such changes or modifications may be made in practice as fairly fall within the scope of my invention.

Having described my invention, what I claim is—

The herein described steering apparatus, 85 consisting essentially of the following elements in combination, viz: the rudder, the steering wheel, the drum connected with the steering wheel and gradually increased in diameter from its middle to its opposite ends 90 so as to enable it to take up slack of a cable, the cable or chain *y*, connected at one end to the rudder, the cable or chain *z*, also connected at one end to the rudder and connected at an intermediate point in its length to the middle of the drum and wound around the drum, the piston cylinder arranged between the contiguous ends of the two cables *y*, *z*, and extending in the same direction as said cables, the piston arranged in said cylinder and having its rod extended through the opposite ends thereof and disposed in the same direction as the cables and also having the opposite ends of said rod connected to the contiguous ends of said cables *y*, *z*, a source of fluid 105 pressure supply, a valve connected with the source of supply and piston cylinder and adapted to effect communication between the source of supply and the opposite ends of the piston cylinder and communication between 110 opposite ends of the piston cylinder and an exhaust and also adapted to lock fluid in the piston cylinder on opposite sides of the piston, a handle *J*, connected with the valve and arranged adjacent to the steering wheel, substantially as and for the purpose set forth.

In testimony whereof I affix my signature in presence of two witnesses.

JOHN BONNER.
